UNITED STATES PATENT OFFICE.

ERASTUS E. WINKLEY, OF LYNN, MASSACHUSETTS.

SOLE-LAYING MACHINE.

1,081,356.

Specification of Letters Patent. Patented Dec. 16, 1913.

Application filed November 18, 1908. Serial No. 463,137.

To all whom it may concern:

Be it known that I, ERASTUS E. WINKLEY, citizens of the United States, residing at Lynn, in the county of Essex and State of Massachusetts, have invented certain new and useful Improvements in Sole-Laying Machines; and I do hereby declare the following to be a full, clear, and exact description of the invention, such as will enable others skilled in the art to which it appertains to make and use the same.

The invention relates to means for performing the operation known as sole laying in the manufacture of McKay shoes, or shoes in which the outer sole is secured to the shoe by pegs or nails.

In the manufacture of the above class of shoes, the sole is adjusted upon the lasted shoe in the desired position, and is secured in place preparatory to the sewing, pegging or nailing operation by a few tacks or nails, which are driven through the sole at the toe and heel of the shoe and hold the shoe in place during the operation of securing it to the shoe. In locating the sole upon the shoe and securing it in place, it is customary for the operator to place the sole in position upon the shoe bottom, while holding the shoe right side up, and to then, while holding the sole in position, turn the shoe over and present the sole to a nail driving mechanism. This manner of locating the sole upon the shoe requires skill and care on the part of the operator, and even then the soles are not uniformly located upon different shoes. It also frequently happens in turning the shoe over after he has carefully located the sole on the bottom of the shoe, that the operator allows the sole to slip from the position in which it was placed, so that it is not secured in the proper location upon the shoe.

It is the object of the present invention to provide devices which will enable the operator to quickly and accurately locate the sole upon the bottom of a shoe, and present the shoe to the nail driving mechanism, without the exercise of any particular care or skill.

To this end one feature of the invention contemplates the provision in a machine for driving nails through the sole of a shoe, of devices for locating a sole on the bottom of a shoe in position for receiving the securing nail, which are so constructed and arranged that they may be withdrawn out

of the way after a nail has been driven, and thus offer no obstruction to the manipulation of the shoe by the operator in thereafter driving any desired number of nails in the sole. The sole locating devices enable the operator to quickly and accurately locate the sole upon the bottom of the shoe, and to drive a nail through the sole, so that there is practically no danger that the sole will become displaced, and then the locating devices immediately move or may be moved out of the way, so that the driving of the succeeding nails may be rapidly and conveniently performed in the usual manner. When the succeeding sole is to be laid, the locating devices may be again returned by the operator into working relation with the nail driving mechanism. Thus the soles may be accurately and uniformly located, and the operation of laying the soles be rapidly performed by a comparatively unskilled operator. The moving of the sole locating devices into and out of working relation with the nail driving mechanism may be effected in any suitable manner, so far as the broader features of the invention are concerned. It is preferred, however, to provide for the moving of the locating devices into working relation with the nail driving mechanism by the operator, and to provide mechanism for withdrawing the sole locating devices from working relation with the nail driving mechanism between two successive operations of the nail driving mechanism, and it is also preferred to so construct the withdrawing mechanism that it will act automatically to withdraw the locating devices during the manipulation of the machine to secure two successive operations of the nail driving mechanism.

The invention further contemplates the provision of locating devices of novel construction and arrangement whereby the soles may be quickly and uniformly located on the bottoms of the shoes, and also the provision of novel adjustments to secure the desired relation between the soles and uppers and uniformity in acting upon rights and lefts.

The various features of the invention will be readily understood from an inspection of the accompanying drawings, in which—

Figure 1 is a side elevation of a machine embodying the features of the invention in their preferred form; Fig. 2 is a front elevation of the devices for positioning the

sole upon the bottom of the shoe; Fig. 3 is a central sectional view on line 3-3, Fig. 2; Fig. 4 is a detail plan view of the devices shown in Fig. 2 on an enlarged scale; Fig. 5 is a similar sectional plan view with the sole engaging devices removed; Fig. 6 is a sectional view on line 6-6, Fig. 3; Fig. 7 is a sectional view on line 7-7, Fig. 3; Fig. 8 is a sectional view on line 8-8, Fig. 7; and Figs. 9, 10 and 11 are detail views showing a stop mechanism for arresting the action of the nail driving mechanism after a single nail has been driven.

The machine shown in the drawings is provided with a nail driving mechanism indicated generally at 1, which corresponds in construction to the nail driving mechanism of well-known machines commonly employed for laying the soles of McKay shoes. The devices for locating a sole upon the bottom of a shoe in position to receive a securing nail are supported and carried upon a support 2, the lower end of which is bifurcated as indicated in Fig. 8, and is pivotally supported upon pivots 3. The support is held in working relation to the nail driving mechanism by means of a toggle comprising the links 4 and 5 connected by the pivot 6. The arms of the link 4 are pivoted at their rear ends upon a pivot pin 7 carried in an adjusting eccentric 8 which is mounted in the standard 9 of the machine. The two side members of the link 5 are pivotally connected at their forward ends with the support 2 by pivot screws 10. A shaft 11 is mounted in the side members of the link 5, and a trip lever 12 is mounted on this shaft between the side members of the link. The under side of the lever 12 at the rear of the shaft 11 is arranged to engage a stop 13 on the link 5, and the upper side of the lever at the rear of the stop 13 is arranged to be engaged by an adjustable stop screw 14 carried by the link 4 and arranged in front of the pivot 6. The trip lever and stops 13 and 14 thus form stop devices for limiting the downward movement of the pivot 6 of the toggle when the toggle is straight, so that the toggle will act as a brace to hold the support 2 in working relation with the nail driving mechanism against the tension of a spring 15 which tends to swing the support rearward and thus move the locating devices carried on its upper end out of working relation with the nail driving mechanism. By adjustment of the eccentric 8, the upper end of the support 2 may be adjusted to bring it into the desired relation with the nail driving mechanism. The pivots 3 at the lower end of the support 2 may also be adjusted forward or back in accordance with the adjustment of the eccentric 8 or to vary the position of the support with relation to the nail driving mechanism, if found desirable.

For this purpose the pivot pins 3 upon which the lower end of the support 2 is mounted extend through slots 16 formed in the supporting bracket 17, and are connected by links 18 with the depending arms of an adjustable lever 19. The lever 19 may be adjusted by means of a stud 20 mounted in a bearing 21 in the bracket 17, and carrying a pin 22 on its forward end which engages vertical slots in the arms of the lever 19. The stud 20 is screw threaded and is provided with adjusting nuts 23 arranged on opposite sides of the bearing 21.

The support 2 is provided at its upper end with a head 2' upon which the devices for engaging the shoe upper and sole and relatively positioning them at the end of the shoe are mounted. The devices for engaging and positioning the upper of the shoe comprise a gage 24 for engaging the end of the upper, two centering gages 25 arranged to embrace the end of the shoe upper, and two side gages 26 and 27 arranged to engage the side of the shoe upper, the gage 26 being employed in positioning the upper of a right shoe and the gage 27 being employed in positioning the upper of a left shoe.

In order that the centering gages 25 may act to uniformly position the ends of the uppers of different shoes, and may also automatically accommodate themselves to variations in the widths of different uppers, these centering gages are held yieldingly in position and are connected to move in unison. In the construction shown, the centering gages are in the form of levers, the front ends of which are shaped to engage the end of a shoe on opposite sides of the center line, and the rear ends of which are pivotally supported upon the pivots 28. The levers are connected to move in unison by intermeshing segments 29 formed on their rear ends, and are held yieldingly in position by springs 30.

In order that the side gages 26 and 27 may be conveniently and accurately adjusted to similarly position the uppers of right and left shoes, these gages are connected so that they are adjusted in unison. In the construction shown, the gages are in the form of levers, the upper ends of which are constructed to engage the side of the upper of a shoe, and the lower ends of which are provided with intermeshing gear segments 31. These gages are pivotally mounted upon a plate 32 carried upon a supporting frame 33. The frame 33 is provided with two rearwardly extending arms, the rear ends of which are pivotally connected at 34 with a bracket 35 which is secured to the support 2. The plate 32 is connected with the frame 33 by bolts 36 which pass through vertical slots in the frame, so that the vertical position of the side gages 26 and 27 may be adjusted.

A link 37 is pivotally connected to the upper end of the plate 32, and the rear end of the link carries a bolt 38 engaged by a thumb nut 39. The bolt passes through a slot 40 in a plate 41 which is secured to the head 2' so that the plate 32 may be adjusted forward and back to adjust the side gages 26 and 27 longitudinally of the shoe.

The devices for engaging and locating the sole of the shoe comprise a gage 42 for engaging the end of the sole, centering gages 43 arranged to embrace the end of the sole, and side gages 44 and 45 arranged to engage the side of a sole, the gage 44 being employed in locating the soles of right shoes, and the gage 45 being employed for locating the soles of left shoes. The arrangement of the sole engaging gages corresponds to the arrangement of the upper engaging gages, and by means of the upper and sole gages, the sole is accurately located upon the bottom of the shoe in position for receiving a securing nail when the nail driving mechanism is thrown into operation.

In order that the extent to which the sole projects beyond the upper at the end of the shoe may be varied, the end gages for the upper and soles are made relatively adjustable, and this relative adjustment is secured in the construction shown by adjusting the end gage for the sole. For this purpose the end gage 42 is carried on a lever 46, one end of which is pivoted at 47, and the other end of which carries a bolt 48 which is engaged by a thumb nut 49. The bolt passes through a slot 50 formed in a link 51 which is pivoted at 52 to the head 2'. By loosening the thumb nut 49, and moving the bolt 48 along the slot 50, the position of the gage 42 may be quickly adjusted to give the desired projection of sole at the end of the shoe.

In order that the centering gages 43 may uniformly position the different soles, and may automatically accommodate themselves to soles having ends of varying width and shape, they are yieldingly held in position and are connected to move in unison. In the construction shown the gages are in the form of levers, the front ends of which are arranged to engage the sole, and the rear ends of which are pivoted at 53 and are provided with intermeshing gear segments 54. The front ends of the levers are yieldingly forced toward each other by the action of a spring 55 connecting the levers.

In order that the sole may be so located that it projects equally on opposite sides at the end of the shoe, or so that the projection of the sole is unequal on opposite sides at the end of the shoe, as may be desirable, the centering gages at the end of the sole and upper are mounted for relative adjustment transversely of the shoe. In order that accurate and convenient adjustment may be made for securing a uniform loca-

tion of the sole on right and left shoes when the projection of the sole on opposite sides at the toe is unequal, means is also provided for determining the relative transverse adjustment of the sole and upper centering gages in either direction. In the construction shown, the relative transverse adjustment of the upper and toe centering gages is secured by mounting the sole centering gages 43 upon a slide 56 mounted for transverse adjustment in the head 2'. One end of this slide is connected by a link 57 with the rear end of a lever 58. The front end of the lever 58 is provided with a recess 59 having diverging sides 60 and 61. A stop pin 62 is arranged to engage any one of a series of holes 63 formed in a plate 64 underlying the lever 58, the holes being arranged in a line midway between the sides 60 and 61 of the recess 59 when the lever is in position to hold the gage carrying slide 56 in its central position. When the pin 62 is in the hole 63 which registers with the narrow end of the recess 59, the lever 58 is held from movement in either direction, and the gage carrying slide 56 is held in central position. When the slide is in this position, the gages 43 are in such relation to the upper gages 25 that there will be an equal projection of the sole on opposite sides at the end of the sole when the upper and sole are positioned between the centering gages and against the end and side gages. If it is desired to secure an unequal projection of the sole on opposite sides at the end of the shoe, the pin 62 may be introduced into any one of the other holes 63, the hole selected depending upon the degree of variation in the projection of the sole desired. When the pin 62 is in one of these holes, the lever 58 may be shifted to bring the side 61 of the recess against the pin when a sole is to be positioned upon a right shoe, and may be shifted to bring the side 60 of the recess 59 against the pin when a sole is to be located upon a left shoe. This secures a shifting of the sole centering gages an equal distance on opposite sides of the centering position in centering the soles of right and left shoes, and thus secures a uniform positioning of right and left soles with the sole projecting to a greater extent on the outer side of the toe than on the inner side.

To avoid excessive movement of the yielding centering gages in introducing the upper and sole, means are provided for varying the distance between opposing gages when in their normal position. This means in the construction shown consists of two conical adjusting nuts 65 and 66, the conical surfaces of which are arranged to be engaged by fingers 67 and 68 projecting from the rear ends of a lever 48 and a lever 25 respectively. By adjusting these nuts 65

and 66 on the screw threaded studs 69 and 70, the space between the opposing surfaces of the gages 43 and between the opposing surfaces of the gages 25 may be varied.

5 The sole side gages 44 and 45, which co-operate with the upper side gages 26 and 27 in relatively positioning the shoe upper and sole transversely of the shoe, are mounted so that a relative adjustment between the side gages for the sole and upper may be secured to vary the extent to which the sole projects at the side of the shoe. In order that the relative adjustment of the two sets of side gages may be accurately and conveniently made to secure a uniform projection of the sole at the sides of right and left shoes, the sole side gages 44 and 45 are connected to be adjusted in unison. In the construction shown, these side gages are in the form of levers, the upper ends of which are arranged to engage the sides of the soles, and the lower ends of which are provided with intermeshing gear segments 71. The side gages 44 and 45 are mounted upon the plate 32 which carries the sole side gages, and are preferably mounted upon the same pivots. The sole and side gages may thus be adjusted in unison longitudinally of the shoe. The sole side gages are held in adjusted position by a bolt 72 carried in one of the gage levers, and engaging a slot 73 formed in the plate 32. The bolt 72 carries the thumb nut 74 which may be conveniently operated in securing the adjustment of the sole side gages. The upper side gages are held in adjusted position in a similar manner by a bolt 75 and thumb nut 76.

In order that the sole and upper may be securely held in position during the driving 40 of the securing nail, means are provided for clamping the sole upon the shoe after it has been located by means of the locating gages. In the construction shown, the centering gages 43 are provided with projecting plates 77 arranged to overlie the under side of the sole when it is in position between the gages, and the side gages 44 and 45 are provided with projecting plates 78 and 79 arranged to overlie the side of the sole when it is in 50 position against the corresponding gage.

These overlying plates form clamping plates against which the sole is forced by a clamping block 80 arranged to underlie the shoe when in position against the gages. The clamping block 80 is arranged to lie below the shoe when the shoe and sole are to be introduced between the gages, so that the sole and shoe may be readily and quickly positioned by the operator. After the sole 60 and shoe have been positioned, the clamping block is forced upward, and the sole and shoe are firmly clamped in position between the block and clamping plates 77, 78 and 79.

In order that the clamping block 80 may 65 be thus operated, it is, in the construction

shown, secured upon the upper end of a rod 81 which extends through a bearing 82 in the upper end of the support 2 and through the head 2'. The lower end of the rod 81 is surrounded by a sleeve 83, and this sleeve is 70 secured to the upper end of a rod 84 which extends through a bearing 85 near the lower end of the support 2 and is pivotally connected to the rear end of a lever 86 by a pin and slot connection 87. A yielding connection is interposed between the rod 81 and the sleeve 83, so that the clamping block 80 is forced upward with a yielding clamping pressure. This connection in the construction shown comprises a block 88 secured 80 to the rod 81 and arranged to play in slots formed in the sleeve 83. The lower end of the sleeve 83 is provided with lugs 89 and springs 90 are interposed between the lugs 89 and the block 88, and are held in place by 85 the rods 91 which pass through the lugs, block and springs. The clamping block 80 is operated by means of a treadle 92 which is connected by means of a link 93 with the front end of the lever 86. When the operator presses his foot upon the treadle 92, the rod 84 is raised and through the springs 90 and rod 81 forces the clamping block 80 yielding against the shoe held by the operator in position against the locating gages. When 95 the treadle is released, it is raised by a spring 94, and the clamping block 80 is lowered to release the shoe.

In securing a sole to the bottom of a shoe, the first securing nail is usually driven 100 through the sole and upper approximately on the medial line of the shoe, and close to the end of the toe. After this nail is driven, the shoe is manipulated by the operator so that the succeeding securing nails are driven in the desired position along the marginal portion of a shoe on each side. In the construction shown, the locating devices are so arranged that when they are in working 105 relation to the nail driving mechanism they 110 act to locate the sole upon the bottom of the shoe in position for receiving the first securing nail.

In order that the shoe may thereafter be readily manipulated by the operator in 115 driving the succeeding securing nails, provision is made for withdrawing the locating devices from working relation with the nail driving mechanism, so that the space below the nail driving mechanism is unobstructed, 120 and the shoe may be manipulated in the usual manner in driving the succeeding securing nail after the first nail has been driven and has secured the sole against accidental displacement. In the construction 125 shown, means is provided for breaking the toggle which holds the support 2 in its advanced position upon the releasing of the treadle 92 and the consequent unclamping 130 of the shoe, so that the support and locating

devices carried thereby are automatically moved back out of the way by the spring 15 when the treadle is released. The means for thus breaking the toggle comprises a dog 95 arranged to operate upon the forward end of the tripping lever 12. The dog 95 is pivoted upon the upper end of a sleeve 96 which is secured to the upper end of the sleeve 83, and the dog is held yieldingly in position with its lower end projecting as indicated in Fig. 3 by a spring surrounding its pivot. When the connections between the lever 86 and the clamping block 80 are raised to clamp the shoe, the dog 95 rides idly up past the end of the trip lever 12 into the position indicated in Fig. 3. When these connections move downward in unclamping the shoe, the dog 95 strikes the front end of the lever 12, rocking it on its pivot, so that the rear end of the lever, acting upon the stop screw 14, forces the front end of the link 4 of the toggle upward, thus breaking the toggle, so that the spring 15 acts to quickly swing the support 2 back against the standard 9. This movement of the support withdraws the locating gages from the end of the shoe, which is left in the hands of the operator in position for further manipulation in driving the succeeding securing nails. When another sole is to be secured upon the bottom of a shoe, the support 2 is drawn forward into the position indicated in Fig. 3, thus straightening the toggle, which acts to hold the locating devices in working relation to the nail driving mechanism. For convenience in thus drawing forward the support 2, handles 97 are secured upon the side members of the link 5 of the toggle below the pivotal connections between the link and the support 2.

For convenience in controlling the operation of the machine, the devices for clamping and unclamping the shoe and for causing the automatic withdrawal of the locating devices from working relation with the nail driving mechanism are operated from the same treadle through which the operator controls the starting and stopping of the nail driving mechanism. With this construction the operator in depressing the treadle will clamp the shoe and start the nail driving mechanism, so that the first securing nail will be driven. After the first nail is driven, the shoe should be unclamped and the locating devices withdrawn, and these operations will be automatically performed in case the operator immediately releases the treadle after depressing it. It is desirable, however, that the nail driving mechanism of these machines be driven at a very high rate of speed, and with a starting and stopping mechanism of the usual construction employed upon these machines, a second nail might be driven before the

treadle was released and the locating devices withdrawn. To avoid this, it is preferred to provide the machine with a starting and stopping mechanism for the nail driving mechanism of such a character that the nail driving mechanism will be operated to drive a single nail and will then be thrown out of operation, regardless of whether the treadle is released or not. With such a construction the treadle must be released after it has been depressed to cause the driving of a nail before the succeeding nail driving operation is performed, and the withdrawal of the locating devices after a nail has been driven, and before the succeeding nail is driven, is insured without requiring any attention or care on the part of the operator.

The starting and stopping mechanism which it is preferred to employ is illustrated in Figs. 9, 10 and 11. As shown in these views, the driving clutch 98 for the nail driving mechanism is engaged by the downward movement of an operating wedge 99, and is disengaged upon an upward movement of this wedge. The operating wedge 99 is carried by the upper end of a frame 100, the lower end of which is provided with a sleeve 101 surrounding the operating rod 102 and guided in a bearing 103 in the bracket 104. A spring 105 is interposed between a collar 106 on the operating rod 102 and the lower end of the sleeve 101, and tends to force the wedge carrying frame 100 upward with relation to the operating rod. The frame 100 carries a roll 107 near its upper end, which is arranged to ride against a cam 108 on the driving shaft of the nail driving mechanism. When the parts are in position for depressing the treadle and starting the machine, the low part of the cam 108 is above the roll 107, and the frame 100 and rod 102 are locked together by a latch 109 which is pivoted on the frame, and is so arranged that its upper end engages a collar 110 on the rod 102, as indicated in Fig. 9. Now when the treadle 92 is depressed, the frame 100 is drawn down with the rod 102, thus drawing down the wedge 99 and engaging the driving clutch. The driving shaft immediately starts to rotate, and the high part of the cam 108 rides over the roll 107 so that the frame 100 is prevented from rising until after the nail driving operation is completed. Immediately after the cam 108 thus locks the frame 100 in its depressed position, the high part of the cam 108 rides against a roll on the upper end of a bell crank lever 111, rocking the lever about its pivot. This movement of the lever forces downward a rod 112 which is connected to the lower end of the lever, and has its lower end arranged to engage a shoulder 113 on the latch 109. The latch is thus disengaged from the collar 102, and the con-

tinued downward movement of the rod 112 carries a cam surface 114 on the rod against the latch, so that the lower end of the rod is disengaged from the shoulder 113. As soon as the high part of the cam 108 passes beyond the roll 107, the frame 100 is moved upward by the spring 105, raising the wedge 99, so that the clutch is disengaged. This brings the parts into the position indicated in Fig. 11. Before the nail driving mechanism can be again thrown into operation the treadle 92 must be released. When the treadle is released the rod 102 moves up into the position indicated in Fig. 9, and the latch 109 engages the rod, locking the frame 100 and rod 102 together, so that the frame will be drawn down upon the succeeding depression of the treadle.

In the drawings I have shown locating devices especially constructed and arranged to properly locate the sole at the toe and forepart of the shoe. It will be understood, however, that the locating devices may be constructed and arranged to relatively position the sole and upper at the heel of the shoe. It will also be understood that features of the invention may be employed in relatively locating a sole and upper at the end of a shoe after the sole and upper have been secured in place at the other end of the shoe. For instance, locating devices comprising sole and upper centering gages may be employed with advantage in centering the sole upon the heel of the upper after the sole has been positioned and secured at the toe of the shoe, or the same devices might be employed for properly positioning the sole at the toe after the sole had been secured in position at the heel.

While I prefer to employ the construction and arrangement of devices shown and described, it will be understood that this construction is not essential to the broader features of the invention, and may be varied and modified without departing from the same.

It will also be understood that the various features of the invention may be used with advantage in constructions in which various of the other features are not embodied.

Having set forth the nature and object of the invention, and specifically described a construction in which the features of the invention may be embodied, what I claim is:—

1. A sole laying machine, having, in combination, a nail driving mechanism, devices for locating a sole on the bottom of a shoe in position for receiving a securing nail, a support for said devices and means for withdrawing the support from working relation with the nail driving mechanism, substantially as described.

2. A sole laying machine, having, in combination, a nail driving mechanism, devices

for locating a sole on the bottom of a shoe movable at the will of the operator into working relation with the nail driving mechanism, and mechanism for withdrawing the locating devices from working relation with the nail driving mechanism between two successive operations of the nail driving mechanism, substantially as described.

3. A sole laying machine, having, in combination, a nail driving mechanism, devices for locating the sole in position for receiving a securing nail, and mechanism acting automatically to withdraw the locating devices between two successive operations of the nail driving mechanism, substantially as described.

4. A sole laying machine, having, in combination, a nail driving mechanism, a shoe support provided with gages arranged to engage and position a shoe upper, and with gages arranged to engage and locate a sole with relation to the upper, and mechanism for withdrawing the support between two successive operations of the nail driving mechanism, substantially as described.

5. A sole laying machine, having, in combination, a nail driving mechanism, devices for relatively locating a sole and upper in position for receiving a securing nail, shoe clamping devices, and mechanism for withdrawing the locating devices from the shoe upon the release of the clamping devices, substantially as described.

6. A sole laying machine, having, in combination, a nail driving mechanism, devices for relatively locating a sole and upper in position for receiving a securing nail, starting and stopping mechanism for the nail driving mechanism, and mechanism for withdrawing the locating devices from the shoe controlled through the starting and stopping mechanism, substantially as described.

7. A sole locating mechanism, having, in combination, devices for relatively positioning a shoe upper and sole transversely of the shoe arranged to engage one side only of the upper and sole, and centering devices for relatively positioning the upper and sole at the end of the shoe adjustable to secure unequal projections of the sole on opposite sides of the end of the shoe, substantially as described.

8. A sole locating mechanism, having, in combination, devices for relatively positioning a shoe upper and sole at the end of the shoe adjustable to secure unequal projection of the sole on opposite sides of the end of either right or left shoe, devices for relatively positioning the upper and sole transversely of a right shoe, and devices for similarly positioning the upper and sole transversely of a left shoe, substantially as described.

9. A sole locating mechanism, having, in

combination, gages arranged to embrace the end of a shoe upper and gages arranged to embrace the end of a sole and locate it upon the shoe, one set of said gages being yieldingly supported and connected to move in unison when separated by the introduction of a shoe or sole, substantially as described.

10. A sole locating mechanism, having, in combination, gages arranged to embrace the end of a shoe upper connected to yield in unison when separated by the introduction of a shoe, and gages arranged to embrace the end of a sole and locate it on the end of a shoe connected to yield in unison independently of the upper gages when separated by the introduction of a sole, substantially as described.

11. A sole locating mechanism, having, in combination, gages arranged to embrace the end of a shoe upper, gages arranged to embrace the end of a sole and locate it upon the shoe, one set of said gages being yieldingly supported and connected to move in unison when separated by the introduction 25 of a shoe or sole, and means for varying the relation of the upper and sole gages transversely of the shoe, substantially as described.

12. A sole locating mechanism, having, in combination, end gages and yielding centering gages arranged to embrace the end of a shoe and sole and relatively position them at the end of the shoe, and side gages for engaging the upper and sole and relatively positioning them transversely of the shoe, substantially as described.

13. A sole locating mechanism, having, in combination, end gages and yielding centering gages arranged to embrace the end of a shoe and sole and relatively position them at the end of the shoe, and two sets of side gages arranged respectively to relatively position the sole and upper of right and left shoes transversely of the shoe, substantially as described.

14. A sole locating mechanism, having, in combination, devices for relatively positioning a shoe upper and sole at the end of the shoe, side gages arranged to engage the side of a sole and upper respectively of a right shoe and relatively position them transversely of the shoe, and similarly and oppositely arranged side gages for relatively positioning the sole and upper of a left shoe, substantially as described.

15. A sole locating mechanism, having, in combination, devices for relatively positioning a shoe upper and sole at the end of the shoe, side gages arranged to engage the side of the sole and upper respectively of a right shoe and relatively position them transversely of the shoe, similarly and oppositely arranged side gages for relatively positioning the sole and upper of a left shoe, and means for relatively adjusting the upper and

sole gages in unison, substantially as described.

16. A sole locating mechanism, having, in combination, devices for relatively positioning a shoe upper and sole at the end of the shoe, side gages arranged to engage the side of the sole and upper respectively of a right shoe and relatively position them transversely of the shoe, similarly and oppositely arranged side gages for relatively positioning the sole and upper of a left shoe, and connections between similar right and left gages for adjusting them transversely in unison, substantially as described.

17. A sole locating mechanism, having, in combination, devices for relatively positioning a shoe upper and sole at the end of the shoe, side gages arranged to engage the side of a sole and upper respectively of a right shoe and relatively position them transversely of the shoe, similarly and oppositely arranged side gages for relatively positioning the sole and upper of a left shoe, and means for adjusting the right and left side gages longitudinally of the shoe, substantially as described.

18. A sole locating mechanism, having, in combination, gages arranged to embrace the end of a shoe upper, gages arranged to embrace the end of a sole and locate it upon the end of the shoe, means for relatively shifting the upper and sole gages laterally to secure unequal projection of the sole on opposite sides of the end of the shoe, and means for determining the relative positions of the gages to secure similar locations of the sole on right and left shoes, substantially as described.

19. A sole locating mechanism, having, in combination, relatively adjustable gages for engaging the end of an upper and sole respectively, yielding centering gages for embracing the end of the upper, yielding centering gages for embracing the end of the sole, and relatively adjustable side gages for engaging the side of the upper and sole respectively, substantially as described.

20. A sole laying machine, having, in combination, a nail driving mechanism, devices for locating a sole on the bottom of a shoe in position for receiving a securing nail having provision for withdrawal from the shoe after a securing nail is driven to leave the shoe free for manipulation in driving succeeding nails, substantially as described.

21. A sole laying machine, having, in combination, a nail driving mechanism, devices for engaging a shoe and sole to locate the sole on the shoe in position for receiving a securing nail, and mechanism for withdrawing the locating devices from engagement with the shoe and sole to leave the shoe free for manipulation in driving succeeding nails, substantially as described.

22. A sole laying machine, having, in com-

combination, a nail driving mechanism, devices for engaging a shoe and sole to locate the sole in position upon the shoe for receiving a securing nail, and mechanism for with-
5 drawing the locating devices from engage-
ment with the shoe and sole between two successive operations of the nail driving mechanism to leave the shoe free for ma-
nipulation during succeeding operations of
10 the nail driving mechanism, substantially as described.

23. A sole locating mechanism, having, in combination, two relatively movable gages held yieldingly in position to embrace the
15 end of a shoe and connected to move in unison when separated by the introduction of a shoe, two relatively movable gages held yieldingly in position to embrace the end of a sole and locate it on the end of a shoe
20 connected to move in unison when separated by the introduction of a sole, and means for relatively adjusting the two sets of gages transversely of the shoe, substan-
tially as described.

25. 24. A sole locating mechanism, having, in combination, end gages for engaging and relatively positioning the ends of a shoe upper and sole, two relatively movable gages held yieldingly in position to em-
brace the end of a shoe and connected to move in unison when separated by the introduc-
30 tion of a shoe, and two relatively movable gages held yieldingly in position to embrace the end of the sole and locate it
35 on the end of the shoe connected to move in unison when separated by the introduc-
tion of the sole, substantially as described.

25. A sole locating mechanism, having, in combination, gages arranged to embrace the
40 end of a shoe upper, gages arranged to em-
brace the end of a sole and locate it upon the shoe, one set of said gages being con-
nected to move in unison toward or from each other independently of the other gages,
45 substantially as described.

26. A sole locating mechanism, having, in combination, two gages connected to move in unison toward or from each other ar-
ranged to embrace and center the end of a
50 shoe upper, and two gages connected to move in unison toward and away from each other independently of the upper gages and arranged to embrace the end of a sole and locate it upon the shoe, substantially as de-
55 scribed.

27. A sole locating mechanism, having, in combination, devices for relatively position-
ing a shoe upper and sole at the toe of a

shoe, plates arranged to overlie the sole, a clamp for engaging the toe of the shoe, and
60 means for operating the clamp to hold the shoe and sole between the plates and clamp, substantially as described.

28. A sole locating mechanism, having, in combination, upper and sole gages for relatively positioning a shoe upper and sole at the toe of the shoe, plates overlying the sole, and a clamp for engaging the toe of the shoe and forcing the shoe toward the plates, substantially as described.

29. A sole locating mechanism, having, in combination, end gages arranged to relatively position the end of the shoe and sole, gages arranged to engage the sole and shoe at the side of the medial line of the shoe,
75 and means for relatively shifting the side gages transversely to vary the projection of the sole for right and left shoes having unequal projection on opposite sides, substan-
tially as described.

30. A sole locating mechanism, having, in combination, end gages arranged to relatively position the end of the shoe and sole, a gage arranged to engage the shoe to one side of the medial line, a corresponding gage for engaging the sole, and means for varying the position of the sole gage for right and left shoes having unequal extension of sole on opposite sides and adjustable means for determining the transverse move-
90 ments of the sole gage, substantially as de-
scribed.

31. A sole locating mechanism, having, in combination, end gages, and relatively movable shoe and sole centering gages mounted to yield relatively to the end gages when engaged by the shoe and sole and arranged to embrace the end of a shoe and sole and relatively position them at the end of the shoe, substantially as described.

32. A sole locating mechanism, having, in combination, end gages, and relatively movable shoe and sole centering gages mounted to embrace the end of a shoe and sole respec-
tively and mounted to yield independently with relation to the end gages when engaged by the shoe and sole and arranged to cooperate with the end gages in relatively position-
10 ing the sole and shoe, substantially as de-
scribed.

In testimony whereof I affix my signature, in presence of two witnesses.

ERASTUS E. WINKLEY.

Witnesses:

N. D. MCPHAIL,
ANNIE C. RICHARDSON.
